UNITED STATES PATENT OFFICE.

FREDERICK R. PETERSON, OF MALDEN, MASSACHUSETTS.

PLASTIC STAIR.

SPECIFICATION forming part of Letters Patent No. 760,752, dated May 24, 1904.

Application filed March 21, 1904. Serial No. 199,113. (No model.)

To all whom it may concern:

Be it known that I, FREDERICK R. PETERSON, a citizen of Sweden, and a resident of Malden, in the county of Middlesex and State 5 of Massachusetts, have invented certain new and useful Improvements in Plastic Stairs, of which the following is a specification.

This invention relates to improvements in plastic or concrete stairways and a metal 10 skeleton supporting-frame, as will hereinafter be more fully shown and described, reference being had to the accompanying drawings, where—

Figure 1 is a top plan view of the invention, showing the cement removed from one 15 of the steps. Fig. 2 is a partial cross-section on the line 2 2 shown in Fig. 1. Fig. 3 is a partial cross-section on the line 3 3 shown in Fig. 1. Fig. 4 is a side elevation as seen from 20 the open or independent side of the stairs. Fig. 5 is a section on the line 5 5 shown in Fig. 1, and Fig. 6 is a side view of the metal supporting-frame as seen from α in Fig. 1.

Similar letters refer to similar parts whenever they occur on the different parts of the 25 drawings.

The invention is applicable to what is termed an "open" or "independent" fireproof stairway, in which both sides of the stairway are 30 free and exposed, as well as to similar stairways in which one or both sides are located adjacent to walls in the building, as may be desired, according to the construction or arrangement of the interior walls of the building. 35

In the drawings, A and B are the respective upper and lower preferably metal 1 floor-beams to which the upper and lower ends of the framework of the stairway are suitably 40 supported in any well-known manner. The metal framework consists of inclined metal stair-supports C D, preferably made of angle-iron, and intermediate such angle-iron supports is located a central support E, preferably 45 made of T-iron, as shown. Only one such T-iron support is shown; but more may be used, according to the width of the stairway.

To the angle-iron D—that is, the exposed side of the stairway—is secured a metal plate 50 or stringer F, which serves to protect the

cement filling G from being defaced or disintegrated, and in stairways that are exposed on both sides such metal stringer is used on both sides of the stairway.

For protecting the edges of the cement steps 55 G', I make use of metal angle-moldings H, which are secured to the center supporting-beam E by means of metal diverging stays or braces I I, riveted to said beam E and angle-moldings, as shown. On the exposed side of 60 the stairway I make on said angle-molding H an angular end extension H' for protecting the exposed end of cement step, as shown. For the purpose of securing and firmly holding the cement step in position relative to the skeleton 65 framework I secure to the angle-molding extensions H' suitable metal angular anchor-strips h h, resting on the upper edge of the metal stringer F or riveted theron, which anchors are embedded in the plastic cement when 70 filled in between the skeleton framework of the stairway.

On the unexposed side of the stairway—namely, the one adjacent to the wall K in Figs. 1 and 5—the stringer F may be dispensed with, 75 as well as the angle-molding extension H', in lieu of which I secure to the end of the angle-molding H and side bar C a horizontal metal strap L, which is attached to the latter and the angle-bar C by means of a vertical metal 80 strap ℓ or hanger, preferably riveted to said parts, as shown, and forming a supporting-bracket interposed between the angle-molding and bar C.

After the parts composing the skeleton 85 metal framework have been assembled the interstices are filled with plastic cement or concrete, which is allowed to set and harden, causing the metal framework to be embedded in the cement, by which a fireproof stairway is 90 produced of great strength and durability.

Having thus fully described the nature, construction, and operation of my invention, I 95 wish to secure by Letters Patent and claim—

1. A skeleton frame for cement-lined stairways consisting of parallel metal side supports, one or more intermediate T-beams, an angle-mold or edge-protector, diverging braces connecting the latter, and the T-beam and a metal stringer secured to the exposed side of the 100

stairway substantially as and for the purpose set forth.

2. A skeleton frame for cement-lined stairways consisting of parallel metal side supports, one or more intermediate T-beams, an angle-mold or edge-protector, diverging braces connecting the latter and the T-beam, a metal stringer secured to the exposed side of the stairway, and metal anchor-plates secured to the angle-mold and adapted to be embedded in the cement or plastic material as set forth.
3. A skeleton frame for cement-lined stairways consisting of parallel metal side supports,

one or more intermediate T-beams, an angle-mold or edge-protector, diverging braces connecting the latter and the T-beam and a supporting-bracket connected to the angle-mold and side support at the unexposed side of the stairway as set forth. 15

In testimony whereof I have affixed my signature in presence of two witnesses. 20

FREDERICK R. PETERSON.
